UNITED STATES PATENT OFFICE.

PHILIP W. MOORE, OF HUBBARD WOODS, ILLINOIS, ASSIGNOR TO THE P & M COMPANY, OF CHICAGO, ILLINOIS, A CORPORATION OF ILLINOIS.

RAIL ANCHOR.

Application filed March 15, 1922. Serial No. 543,999.

To all whom it may concern:

Be it known that I, PHILIP W. MOORE, a citizen of the United States, residing at Hubbard Woods, in the county of Cook and 5 State of Illinois, have invented certain new and useful Improvements in Rail Anchors, of which the following is a specification.

My invention relates to a rail anchor or anti-creeper of the type comprising two 10 members provided with jaws for gripping the opposite edges of the base of the rail to which the device is applied and having an interlocking tongue and groove engagement one with the other under the rail base, one 15 of the members being formed with an extended bearing face adapted to engage one side of the tie against which the anchor is placed.

The object of the invention is to provide 20 certain improvements in a rail anchor of this type whereby the strength of the device under the stresses to which it is subjected in service is increased, in comparison with rail anchors of this type, as heretofore used; 25 its range of adjustability to rail bases of different widths made greater; the device rendered easier of application to the rail and its correct adjustment thereon and against the tie assured; and the manufacture of the 30 parts facilitated and cheapened. Rail anchors are manufactured, shipped and used often in large quantities. They are subjected to very intense stresses when functioning properly to check the forward creep- 35 ing of the rails, which stresses tend to distort, stretch or tear the metal. On the other hand, the necessity for economizing metal in the manufacture of these devices and for minimizing freight charges in their trans- 40 portation makes it desirable to reduce weight as far as can be done consistently with strength and durability. Inasmuch as rail anchors are applied to the rails in large numbers and usually by unskilled labor, and,

45 as it often happens that the ties against which the anchors bear are of irregular shape or stand obliquely to the rail, it is very important, since the holding power of a rail anchor depends upon its correct ad- 50 justment, that the parts of the anchor be so constructed as to be capable of a quick and accurately adjusted application to the rail. It is also important that the anchors be 55 adapted to fit rails having base flanges of different widths without sacrificing holding

power or strength when used on the rails of greater widths.

My present invention provides a rail anchor which, it is believed, by a novel construction that combines all of the advantageous features above noted, is practically much superior to any rail anchor of this general type heretofore made and used.

An anchor constructed in accordance with the invention is illustrated in the accom- 60 panying drawing wherein—

Fig. 1 is a plan view of the device shown as applied to a railroad rail, the latter being illustrated in sectional plan.

Fig. 2 is a side elevation of the device, 70 with the rail in section, taken on line 2—2 of Fig. 1.

Fig. 3 is a view, in perspective, of one of the members constituting the anchor, and

Fig. 4 is a similar view of the other mem- 75 ber.

Referring to the drawing, 10 designates the base flange of a railroad rail and 11 one of the ties on which the rail is supported.

The anchor consists of two members, a 80 clip, designated A, and a mate, as it will be hereinafter termed, designated B. The clip consists of a preferably flat plate 12 formed at one end with a jaw 13 and at the other end with a channeled offset portion 14 pro- 85 viding an upwardly opening groove 15 which is slightly oblique with respect to the jaw 13. The rear edge of the clip, that is to say, the edge remote from the tie against which the anchor bears, is formed with a 90 strengthening flange 16 extending around the jaw 13 and, at the other end, united with the channeled offset portion 14. The forward edge of the plate is formed with a depending flange 17 which also extends around 95 jaw 13 and, at the other end of the clip, is enlarged to provide a preferably flat tie abutting web 18 braced by a triangular strut 19.

The plate 12 is widened by enlargement 100 forwardly at the end provided with groove 15 and groove 15 extends all the way across this place of maximum width of the plate. The tie abutting web 18 is flush with the front edge of the plate at its widened end 105 and extends to and is united with the channeled offset 14.

The mate B is provided with a jaw rigidified by flanges 21 and with a depending tongue 22 which is slightly oblique with 110

respect to jaw 20. The tongue 22 is designed to fit into the groove 15 in the clip and the obliquity of the groove and tongue is such that jaw 20 on the mate is drawn toward jaw 13 on the clip when the mate is driven toward the tie against which the anchor bears. The mate is preferably formed with a flat surface 23 which aligns with the flat upper surface of the clip, both these surfaces bearing against the under side of the rail base flange.

The anchor is applied to the rail by hooking the jaw 13 of the clip on one edge of the rail base 10 with the web 18 of the clip bearing against the tie 11 and then placing the mate on the other edge of the rail base with its tongue 22 in groove 15 of the clip and driving the mate toward tie 11 until a tight fit of the parts of the anchor on the rail base is effected. The jaw 13 being set back with respect to the bearing web 18 stands away from the tie. The creeping stress of the rail, therefore, tends to produce a cramping grip on the rail of the anchor as a whole as well as the wedging action of the parts thereof so as to augment the holding power of the device. The offsetting of jaw 13 has another purpose. Ties are frequently irregular in shape or skewed in the road bed. If the front face of jaw 13 were in line with web 18 the irregularity or skewed position of the tie might be such that in applying the clip the jaw would touch the tie while the other end of the clip stood away from the tie. Under these conditions when the mate was driven into place there would be a tendency for the clip to turn on the rail making the application of the anchor difficult and the security of its hold on the rail base uncertain. By forming the anchor so that jaw 13 stands back of the bearing web 18 some latitude is allowed for irregularities in the shape and position of the tie so that in most cases, at least, the undesirable conditions above noted will not exist. By effecting this offset of the jaw 13 through narrowing this end of the clip metal is economized at a place on the anchor where such economy can be effected without sacrificing strength. It is desirable that the other end of the clip be as wide as possible, in the first place, because the wedging engagement of the mate against the clip requires strength and rigidity in this part of the anchor, and in the second place, in order that, since the stability of the tongue and groove wedging engagement depends upon having the tongue and groove in engagement for a considerable distance, the tongue and groove may be as long as possible. This is important when the anchor is used on a relatively wide rail since with a rail of more than average width (referring to the range of adjustability of the anchor) the mate cannot be driven as far toward the tie as with rails

having base flanges of lesser width. The tie abutting web 18 is arranged in line with groove 15 so that the mate when applied to the clip is driven directly toward the place of bearing of the clip on the tie. The web 18 is flush with the edge of the plate 12 of the clip, at the place of maximum width of the plate, is preferably flat and at substantially right angles with the plate, and is continuous with the rigidifying flange 17 on the forward edge of the plate. A rail anchor having its tie abutting web flush with the edge of the body of the clip or equivalent part, has been found to be stronger than a construction involving the offsetting of the web forwardly from the bar or plate constituting the body of the clip. The advantage of having the tie abutting member stand forwardly of the body of the clip is that the clip is held away from the tie so as to allow greater range of movement of the mate for rails of different widths of base flange. But experience has shown that this expedient of offsetting the flange is likely to result in structural weakness. The creeping stresses developed in the rail are likely to tear the body of the clip from the tie abutting member. The spacing of the clip back from the tie may be accomplished by a tie abutting web which is flush with the edge of the clip at the top and is curved forwardly at the bottom. But this expedient adds to the cost of manufacture by making the molding of the clip more difficult. In the improved anchor of my present invention the increased range of adjustability is provided for without either weakening the anchor structurally or increasing its cost of production. The same construction increases to a maximum the possible extent of interlock, that is, the amount of surface in contact between the clip and mate. The upper surfaces of both clip and mate and the surfaces bearing against the bottom of the rail base flange are flat. Experience has shown that where these surfaces are curved there is a tendency for the curved portions to straighten out under wedging and creeping stresses so as to impair the effectiveness of the hold of the device on the rail. The web 18 strengthens the offset channeled structure 14 which receives the tongue of the mate as does also the strut 19, the primary purpose of which is to take the thrust of the web 18 against the tie.

I claim:

1. A rail anchor consisting of clip and mate members having a wedging tongue and groove engagement with each other under the rail base at one side thereof and formed with jaws to engage opposite edges of said rail base, the body of the clip being formed at the place of said tongue and groove engagement with a surface to bear against a

tie, and said clip being provided with an extended tie abutting web, the front surface of which is flush with the aforesaid surface and this end of the clip being wider than the 5 jaw end so that the jaw on the clip normally stands away from the tie against which the anchor bears.

2. A rail anchor consisting of clip and mate members having a wedging tongue and 10 groove engagement with each other under the rail base at one side thereof and formed with jaws to engage opposite edges of said rail base, the body of the clip being formed at the place of said tongue and groove engagement with a surface to bear against a tie, and said clip being provided with an 15 extended flat, depending tie abutting web, the front surface of which is flush with the aforesaid surface and this end of the clip 20 being wider than the jaw end so that the jaw on the clip normally stands away from the tie against which the anchor bears.

3. A rail anchor consisting of clip and mate members having a wedging tongue and 25 groove engagement with each other under the rail base at one side thereof and formed with jaws to engage opposite edges of said rail base and with flat, aligned surfaces to bear against the under side of the rail base, 30 the inner edges of which surfaces are substantially in contact with just enough clearance to allow relative movement as between the members, the clip being provided with an extended tie abutting web at the end engaged by the mate and this end of the clip 35 being wider than the jaw end so that the jaw on the clip normally stands away from the tie against which the anchor bears.

4. A rail anchor comprising a clip consisting of a metal plate formed at one end with a jaw, the other end being extended forwardly to give it greater width than the 40 jaw end of the plate and formed at its place of maximum width with a depending tie 45 abutting web, flush with the edge of the plate, and with a groove extending the full width of the bar and slightly oblique with respect to said jaw, and a mate having an oblique rib to enter the groove in the clip 50 and formed with a rail engaging jaw.

5. A rail anchor comprising a clip consisting of a metal plate formed at one end with a jaw, the other end being extended forwardly to give it greater width than the 55 jaw end of the plate and formed at its place of maximum width with a depending tie abutting web, the front surface of which is flush with the edge of the plate, and with a groove 60 extending the full width of the bar and slightly oblique with respect to said jaw,

and a mate having an oblique rib to enter the groove in the clip and formed with a rail engaging jaw, said mate and clip having flat, aligning, upper surfaces which bear against the under surface of the rail base 6 the inner edges of which surfaces are substantially in contact with just enough clearance to allow relative movement as between the members.

6. A rail anchor comprising a clip consisting of a metal plate formed at one end with a jaw, the other end being extended forwardly to give it greater width than the 70 jaw end of the plate and formed at its place of maximum width with a depending tie 75 abutting, flat web, the front surface of which is flush with the edge of the plate and at right angles thereto, and with a groove extending the full width of the bar and slightly oblique with respect to said jaw, and a mate 80 having an oblique rib to enter the groove in the clip and formed with a rail engaging jaw, said mate and clip having flat, aligning, upper surfaces which bear against the under surface of the rail base, the inner edges 85 of which surfaces are substantially in contact with just enough clearance to allow relative movement as between the members.

7. A rail anchor consisting of clip and mate members having a wedging tongue and 90 groove engagement with each other under the rail base at one side thereof and formed with jaws to engage the opposite edges of said rail base, the clip being provided with an extended tie abutting web at the extreme 95 end of the portion of the clip engaged by the mate the front face of which is flush with the front edge face of the clip and this end of the clip being formed so that it projects forwardly beyond the forward edge of 100 the jaw end of the clip, for the purpose described.

8. A rail anchor comprising, in combination, a clip consisting of a flat plate formed at one end with a jaw, the other end of the 105 plate being widened to project forwardly beyond the jaw and formed at its place of maximum width with a depending, channeled offset portion providing an oblique upwardly opening groove, the plate having 110 flanges along its rear and forward edges, the latter being provided at the place of maximum width of the plate, with an enlargement constituting a tie abutting web the front face of which is flush with the 115 front face of said web, and a mate formed with a rail base engaging jaw and an oblique, depending tongue adapted to enter the groove in the clip.

PHILIP W. MOORE.
